United States Patent Office

Des. 204,279
Patented Apr. 5, 1966

204,279 GOLF CLUB HEAD

William J. Walker, Springhill, La., assignor to Topspin
Putter, Inc., Springhill, La., a corporation of Louisiana

Filed Mar. 17, 1965, Ser. No. 84,314

Term of patent 14 years

(Cl. D34—5)

The broken lines indicating a fragmentary portion of a shaft are for illustrative purposes only.

I claim:

The ornamental design for a golf club head, as shown and described.
